ATTORNEYS.

UNITED STATES PATENT OFFICE

LEE G. VOORHEES, OF LONG ISLAND CITY, NEW YORK, ASSIGNOR TO AXWELD ACETYLENE COMPANY, A CORPORATION OF WEST VIRGINIA

STORAGE GASOMETER

Application filed July 14, 1927. Serial No. 205,763.

This invention relates to gasometers of the type having an inverted bell floating upon a liquid, and more particularly to a means of compensating for variations in the pressure of the gas stored within the bell.

It is well known in the art that a gas storage bell weighs less when it is immersed to a large extent in a buoyant liquid than when it is immersed to a less extent. This variation in the weight of the bell, due to its degree of immersion, causes a corresponding variation in the pressure of the gas within the bell. This variation in pressure is especially objectionable in gasometers used for the storage of acetylene gas at a low pressure.

Pressure reducing valves have been used in the delivery lines from these gasometers to eliminate the fluctuations in pressure but they are unsatisfactory because they require considerable attention to keep them in operating condition and, because the initial pressure must be higher than would otherwise be necessary.

Therefore, the object of this invention is a gasometer bell in which the gas pressure remains constant regardless of the depth of its immersion due to the volume of gas within it. How this is accomplished will be readily apparent from the description and illustration.

In the drawing which is a vertical section of the invention 3 designates an outer container or tank of the gasometer having preferably a cylindrical side wall 3' and a flat bottom 3''. The shape of this tank is not essential and it may be altered to suit various individual conditions. Within the tank 3 is a liquid 4 which is preferably water though others such as oil may be used when desirable. Floating upon the water 4 is an inverted bell 1 having preferably a cylindrical side wall 1' and a top 1'' closing its upper end. The shape of the side wall may be other than cylindrical and, also, the top may be of other shapes such as conical or spherical. Pipes or conduits 2 and 2' convey gas to and from the interior of the bell 1. So far the gasometer is of a conventional design well known in the art.

50 A circumferential flange 6 is attached to

the inside of the bell 1 at a point 7 near its open end and extends inward a short distance to a point 7' where it joins a depending cylindrical member 6'' which extends downward to a point approximately in line 55 with the lower edge of the bell 1. The flange 6 and the cylindrical member 6'' together with the lower portion of the wall 1' below the point 7 form a chamber 5 open only at the bottom to the water 4. Due to its function it is called a compensating chamber and it may be considered as a part of bell 1. The wall 6'' and the top 6 of the compensating chamber 5 may be integral or they may be separate members joined at 7'. Or, the compensating chamber may be made complete in itself and then joined to bell 1. Furthermore, it may have a closed bottom with one or more openings of various sizes therein and still be within the scope of this invention and its method of operation. The compensating chamber 5 is shown within the bell 1 but this position is not essential as it may be either inside, outside, or both.

During the operation of the gasometer the 75 bell 1 may be nearly full of gas so most of the side wall 1' is out of the water 4, or it may be nearly empty so most of the side wall 1 is immersed in the water 4. As the pressure exerted upon the gas within bell 80 1 is controlled by the weight of the tank with the accessories thereon and, as the bell has less weight when its side wall 1' is immersed in the water 4, consequently, the pressure upon the gas is greater when the bell is full 85 than when it is empty. The purpose of chamber 5 is to compensate for the variation in the weight of the bell 1 and, consequently, the variation in the pressure of the gas within it.

The air within chamber 5 displaces a definite volume of water. The weight of this volume of water is then the measure of the lifting or buoyant effort upon the bell 1. When the bell 1 is nearly full of gas it is 90 mostly above the surface of the water 4 and the chamber 5 is then just below the surface. In this position the pressure of the water upon the air within chamber 5 is but a small amount so it is compressed but little. There- 95

fore, it has its greatest volume and buoyant effort within the range of its operating movement. As gas is withdrawn from the interior of bell 1 it gradually sinks. As it sinks a greater portion of its side wall is immersed and it becomes lighter. Also, as the chamber 5 sinks the water pressure upon it becomes greater and the air within it is compressed into a smaller space. Thus, the chamber displaces less water than before and is accordingly buoyed up with less force. Therefore, as the bell 1 sinks its side wall 1' becomes lighter and its compensating chamber becomes heavier, and by properly proportioning the volume of air in chamber 5 to the volume of metal in the side wall 1', the variation in the weight of the side wall 1 may be compensated by the opposite variation in the chamber 5.

20 In addition to the air in chamber 5, there is always a certain volume of water as designated by the numeral 9. This volume is controlled by the pressure of the water upon the air within chamber 5. When the chamber is near the surface of the water the pressure of the water upon the air within the chamber is but little. Consequently, the air is compressed but a small amount and there is but a small volume of water in the chamber. 25 When the chamber is more deeply submerged, the pressure of the water upon the air within the chamber is greater. Therefore, the air is compressed to a greater extent and there is a larger volume of water within the chamber.

30 As the bell 1 is filled with gas the variable forces act in the opposite direction. For instance, as the side wall 1' emerges from the water 4 it becomes heavier, and as the chamber 5 rises toward the surface of the water 4 the air within it expands, due to the reduced pressure of the water upon it, so it displaces more water and, consequently, becomes lighter.

35 In some cases the buoyant effect of the chamber 5 may reduce the weight of the tank 1 so it does not exert sufficient pressure upon the gas within it. If so, a weight may be added to the bell 1 as shown at 10. If the position of the weight tends to make the tank top heavy and unstable it may be added to the bottom or submerged portion of the tank.

40 Guides of various kinds are frequently used to hold the bell 1 in a vertical position and to prevent it from coming in contact with the tank 3, but they are well known in the art and are omitted from the illustration for the sake of clearness. Also gas supply and discharge may be through a plurality of conduits such as 2 and 2', and a vent pipe may be used to conduct excess quantities of gas away from the tank in a manner well known in the art. These and other changes

may be made without altering the scope of this invention or its method of operation.

I claim:

1. In a storage gasometer, the combination of a tank adapted for holding a liquid; a bell adapted for partial immersion in said liquid and also for containing a gas upon which said bell exerts a pressure; said gasometer being provided with suitable means including gas inlet and outlet conduits for varying the quantity of gas within said bell and thereby its degree of immersion; and a submerged chamber connected to said bell and adapted to contain a gas in communication only with said liquid through an opening provided in the wall of said chamber below said gas through which said liquid compresses said gas and varies its buoyant effect on said bell according to its degree of immersion. 70

2. In a storage gasometer, the combination of a tank adapted for holding a liquid; a bell adapted for partial immersion in said liquid and also for containing a gas upon which said bell exerts a pressure; said gasometer being provided with suitable means including gas inlet and outlet conduits for varying the quantity of gas within said bell and thereby its degree of immersion; and an annular chamber connected to said bell and adapted to contain a gas in communication only with said liquid through an opening provided in the wall of said chamber below the portion occupied by said gas and through which said liquid compresses said gas and varies its buoyant effect on said bell according to its degree of immersion. 90

3. In a storage gasometer having a tank, a liquid in said tank and a bell partially immersed in said liquid; a compensator attached to said bell and comprising a submerged chamber adapted to contain a gas and having an opening therein below said gas and in communication only with said liquid by which said gas is compressed so its buoyancy is reduced as the depth of immersion of said compensator is increased. 105

4. In a storage gasometer, the combination of a tank adapted for holding a liquid; a bell adapted for partial immersion in said liquid and also for containing a gas upon which said bell exerts a pressure; a weight on top of said bell; said gasometer being provided with suitable means including separate gas inlet and outlet conduits for varying the quantity of gas within said bell and thereby its degree of immersion; and a chamber located within said bell and having a wall formed by an immersed side wall thereof, said chamber being adapted for containing a gas that may be compressed by said liquid through an opening in the wall of said chamber below the portion thereof occupied by said gas. 115

5. In a storage gasometer having a tank; a liquid in said tank; a bell partially im- 130

mersed in said liquid; and a compensator attached to said bell comprising an annular chamber submerged in said liquid, adapted to contain a gas, and having an opening 5 therein below said gas in communication only with said liquid by which the degree of compression of said gas is varied by the depth of immersion to vary the buoyancy of said compensator.

10 In testimony whereof, I affix my signature.

CERTIFICATE OF CORRECTION.

Patent No. 1,878,211.

September 20, 1932.

LEE G. VOORHEES.

It is hereby certified that the name of the assignee in the above numbered patent was erroneously written and printed as "Axweld Acetylene Company", whereas said name should have been written and printed as Oxweld Acetylene Company, as shown by the records of assignments in this office; and that the said Letters Patent should be read with this correction therein that the same may conform to the record of the case in the Patent Office.

Signed and sealed this 29th day of November, A. D. 1932.

(Seal)

M. J. Moore,
Acting Commissioner of Patents.
